US0D1107925S

(12) **United States Design Patent** (10) **Patent No.:** **US D1,107,925 S**
Meier et al. (45) **Date of Patent:** **** Dec. 30, 2025**

(54) **PRODUCTION DEVICE FOR THERAPEUTIC FOAM**

(71) Applicant: **SANTA ISABEL INTERNATIONAL FOUNDATION**, Piso (PA)

(72) Inventors: **Tim Meier**, Gelsenkirchen (DE); **Felix Pott**, Wuppertal (DE)

(73) Assignee: **SANTA ISABEL INTERNATIONAL FOUNDATION**, Piso (PA)

(**) Term: **15 Years**

(21) Appl. No.: **29/917,395**

(22) Filed: **Nov. 20, 2023**

Related U.S. Application Data

(62) Division of application No. 35/515,556, filed on May 11, 2022 (U.S. filing date under 35 U.S.C. 384), and having an international filing date of May 11, 2022, now Pat. No. Des. 1,082,014.

(57) **CLAIM**

The ornamental design for a production device for therapeutic foam as shown and described.

DESCRIPTION

FIG. 1 is a front view of a production device for therapeutic foam showing my new design.

FIG. 2 is a back view thereof.

FIG. 3 is a left side view thereof.

FIG. 4 is a right hand side view thereof.

FIG. 5 is a top view thereof.

FIG. 6 is a bottom view thereof; and,

FIG. 7 is a perspective view thereof.

The broken lines in the drawings illustrate portions of the production device for therapeutic foam that form no part of the claimed design.

1 Claim, 7 Drawing Sheets
